UNITED STATES PATENT OFFICE.

ROBERT WM. HOMAN, OF BROOKLYN, NEW YORK, ASSIGNOR TO THE
FARREN BROS. COMPANY, OF CONNECTICUT.

BED-BOTTOM.

SPECIFICATION forming part of Letters Patent No. 378,397, dated February 21, 1888.

Application filed February 24, 1885. Serial No. 156,716. (No model.)

To all whom it may concern:

Be it known that I, ROBERT WM. HOMAN, a citizen of the United States, and a resident of the city of Brooklyn, Kings county, and State of New York, have invented certain new and useful Improvements in Spring Bed-Bottoms, of which the following is a specification, reference being had to the accompanying drawings, forming a part thereof, of which—

10 Figure 1 is a bottom view of my improved bed-bottom open, and showing jointed cross-links in position and in combination with parallel slats. Fig. 2 is a sectional edge view. Fig. 3 represents a bottom view of my improved bed with the slats closed; Fig. 4, section of cross-jointed slat-connection; Fig. 5, modification of Fig. 4, showing the links connected separately to the sliding clip; Fig. 6, a modification in manner of attaching links to 20 the slats.

My invention relates to that class of bed-bottoms provided with slats and coiled springs adapted for lateral adjustment; and it consists in the combination and arrangement, with a 25 series of slats and coiled springs, of a series of double cross-jointed links and slides embracing the slats, and also of a combination, with a series of lower or supporting slats, of an upper or elevated side slat located upon each side 30 of the said bed, sustained by an angular or bent arm connecting the upper and lower outer slats, as will be hereinafter more fully described.

The object of the first part of my invention 35 is to insure a uniform parallel movement of the lower slats in unison when adjusted for different widths of bed-frames by contrivances that leave the upper surface of the lower slats nearly bare, and therefore less liable to afford a 40 hiding-place for vermin than those provided with joints above, and also to prevent undue endwise movement of the slats beyond the others by means of the peculiar link-connection solely.

45 The object of the second part of my invention is to insure possibility of the folding or closing of all the slats tightly and uniformly together side by side in packing without requiring other means than the cross-jointed 50 links specified to insure the objects specified.

In the drawings, A represents the slats arranged parallel in their relation to each other;

B, slats elevated above the others, A, at each side of the bottom, which not only serve to connect the row of springs thereunder, but also 55 to prevent their tilting when such slats are connected with the lower ones by the angle of flexible brace, hereinafter specified.

D are flexible arms or connections, (more clearly shown in Fig. 2 of the drawings,) composed in the particular instance of a suitable strip of narrow springy metal bent at an angle, one end of which is secured to the top slat, B, and the other to the slat or slats A below.

E are links of metal jointed together substantially at three points, or as shown in Figs. 1 and 3 in the drawings, the object of this double-jointed arrangement of links being to connect the slats A in such manner as to prevent undue end motion of the said lower slats 70 and at the same time insure a more firm support for the entire structure.

It will be observed that Fig. 1 of the drawings shows the links E pivoted or jointed to the slats A at or near the extreme end of the latter. This is preferable, yet not essential, as will appear obvious to those skilled in the art, as the links E may be hinged to the slats A at the opposite point and the slide-clip F operate between the end of the slat and 80 the rivet or hinged point of connection, as shown in Fig. 6, representing such modification.

Fig. 4 represents the ends of two links overlapping each other, with a bolt or rivet passing through them and the back of the clip by which they are hinged together, while Fig. 5 represents a connection of the same parts by two rivets or bolts without the overlap of the links, as in Fig. 4.

The slide is so formed as to clasp around or embrace the edges of the slats A, to which they are attached and upon which they are adapted to slide when operated, all of which will be readily understood by one skilled in the art to which the invention pertains. The parallel slats may be made of any suitable material, although I prefer, however, thin metal as being the most proper, owing to the peculiarity of the construction of the other parts. In this instance the cross-jointed links are represented as united by rivets, although it is obvious that screws, clips, or other means may be employed for uniting the parts. The

coiled springs are of the kind and character well known for such purposes, and are secured to the lower slats, A, in this instance by rivet. The upper part, excepting the row 5 immediately under the top slats, B, is left free. The angle-brace, which is rigidly riveted to the outer, upper, and lower rails, serves to properly support and retain the outer in position and prevent undue tilting, 10 and by means of which the center rows of slats are maintained in their respective proper position. The cross-jointed links, which are riveted pivotally to the ends of the lower slats, as shown, prevent independent end movement 15 of the slats, and the several parts are held as an entirely more firmly than when a connection of single connected links is employed, and all undue lateral strain to the coiled springs is prevented by the suspended angle-arm and slat, and the central springs are allowed to act freely and without the necessity 20 of connecting them together at their tops, except as previously stated.

I do not wish to be understood as claiming, 25 broadly, a bed-bottom or spring-mattress formed of slats, springs, and a support for an upper side rail or slat, as I am aware that slats located parallel with each other supporting coiled springs are not new. I am also aware 30 that with the combination of slats and coiled springs links for uniting said slats have been used for the most part single and not cross-jointed nor secured to the slats, as shown in the drawings forming a part of my present application. Neither do I claim an arm or support, broadly, for sustaining side rails or slats 35 above the base-slats, as I am aware that an arm of a similar character has been previously shown. My device differs materially from this 40 in that the arm or support in my invention is, so to speak, of flat metal and in form "half-elliptic," one end of which is firmly secured to the outer lower base-rail and the other to the upper "side rail" in a manner permitting 45 the slats to close closely together side by side, and also to prevent the upper or side slat from undue end movement.

Having thus set forth my invention, what I

claim as new, and desire to secure by Letters Patent of the United States of America, is—

50

1. In a spring bed-bottom, the combination, with a series of slats united together by double cross-jointed links, one end thereof attached to or near the end of said slats and the other to sliding devices or clips embracing said slats, 55 adapted for simultaneous adjustment, and each held and supported in parallel relation to each other, of the two outer slats secured together, one of which is supported above the other by means of a bent springy arm of metal, in addition to the coiled springs, substantially as and for the purpose set forth.

2. A spring bed-bottom consisting of a series of parallel slats forming a base-support, the combined width of which is adapted for simultaneous expansion and contraction by means of double cross-jointed links and sliding clips united together, said links extending across, connecting with, and sustaining each slat in a fixed parallel and endwise relation to each other, a series of coiled springs, and two elevated side slats connecting with and supported above the outer slats of the former, all arranged to operate as described.

3. In a spring bed-bottom, the combination, 75 with a series of parallel base-slats united at or near their ends by double cross-jointed connecting-links, sliding clips, and coiled springs, of one or more angular springs rigidly secured to and connecting the outer base-slats and the 80 said elevated side slats, substantially as and for the purpose set forth.

4. In a spring bed-bottom, the combination of a series of parallel base-slats, each connected, supported, and adapted for lateral adjustment by means of double-jointed cross-links, one end of which is pivotally connected to said slats and the other to sliding clips, 85 coiled springs, elevated side slats, and flat angularly-arranged springs D, connecting and 90 supporting the latter, as described.

ROBERT WM. HOMAN.
